UNITED STATES PATENT OFFICE.

FRANCIS F. RANIVILLE, OF GRAND RAPIDS, MICHIGAN.

METHOD OF AND APPARATUS FOR PACKAGING BELTS.

Application filed April 23, 1921. Serial No. 464,050.

To all whom it may concern:

Be it known that I, FRANCIS F. RANIVILLE, a citizen of the United States of America, residing at Grand Rapids, in the 5 county of Kent and State of Michigan, have invented certain new and useful Improvements in Methods of and Apparatus for Packaging Belts; and I do hereby declare the following to be a full, clear, and exact description of the invention, such as will enable others skilled in the art to which it appertains to make and use the same.

The present invention relates to a method of inserting belting in a package adapted 15 to contain the same, being particularly concerned with a method and an apparatus for carrying out the same for simultaneously coiling and positioning the belting within the package. The invention is particularly applicable for the handling of sewing machine belts though not limited in any respect thereto. With my invention, it is designed that a length of belting shall be inserted 20 at one end into the outer container for the same being grasped at its inserted end and coiled into a compact coil with a simultaneous pulling in of the length of belting into the package, which is afterward sealed to preclude escape of the 25 belting from the package. It is a primary object and purpose of the invention to accomplish the above described ends in a simple and economical manner and with speed so that the production of the belt 30 packages in quantity may be had, the steps of the method being simple and such mechanism as is required being very simple and durable in its construction and operation.

For an understanding of the invention, 35 reference may be had to the following description, taken in connection with the accompanying drawings, in which,

Fig. 1 is a side elevation, with parts broken away and shown in section, illustrating the machine used for the accomplishment of the method.

Fig. 2 is a horizontal section through the upper part of the machine the section being taken on a plane between the two upper 45 blocks thereof.

Figs. 3 and 4 are transverse vertical sections through the upper part of the machine, and illustrating the blocks noted in two different positions, and

Fig. 5 is a perspective view of the belt package, a portion of one side of the pack-

age being broken away to illustrate the belt coil within the same.

Like reference characters refer to like parts in the different figures of the drawings.

In the construction of the machine used, any suitable supporting table 1 may be used, as the upper portion of a bench or the like to which two spaced apart vertically extending brackets 2 are secured by screws or like fastenings, a rod 3 extending between the upper ends of the brackets and mounted for rotation therein and on which a short cylinder 4 is eccentrically mounted. A handle 5 extends from the cylinder 4 whereby the same may be turned to different positions manually.

Four rods 7 are connected to the table 1 and extend upwardly therefrom, being spaced apart from each other. A spring 8 is placed around each rod and rests at its lower end on the table. A lower block 9 is placed on the rods, there being openings through the block for the passage of said rods, and springs 8 normally serve to elevate the block a short distance above the table, the block resting on the upper ends of said springs. A second spring 10 is placed around each rod 7 and rests at its lower end on the lower block 9. A second upper block is located above the lower block, and rods 7 passing loosely therethrough, and this upper block is normally elevated a distance above the lower block by the springs 10 on the upper ends of which the upper block rests. The rods 7 are equipped with heads 7^a at their upper ends preventing disengagement of the upper block 11 from the rods and the eccentrically mounted member 4. Member 4 lies immediately above the upper side of block 11, it being apparent that with the turning of the member 4 from one position, as shown in Fig. 3 to that shown in Fig. 4, the blocks will be forced to a lower position, 100 springs 8 and 10 being compressed, the same acting as soon as released by returning the member 4 to initial position to carry the blocks back to upper positions, as shown in Figs. 1 and 3.

A plate 12 formed at one side with an upturned lip 13 is set in the upper side of the lower block 9, the lip being located beyond the side of the block as shown. Two bars 14 are attached to the upper side of the lower block, one at each side of the plate 12, and angle guides having depending legs 15

are connected to the under side of the upper block so as to pass just within the inner sides of said bars 14. The bars 14 serve to space the blocks and hold the same from approaching each other any nearer than the thickness of the bars when the same are forced into lower position, and the guide flanges 15 serve as guides for the belt container which is adapted to be placed between the two blocks, and which comprises narrow elongated sides 16 and a front 17 in which a circular opening 18 is made, together with a back 19 paralleling the front 17, the ends of the container being open. This container is made from a single sheet of relatively stiff paper or paper board folded to the shape described, and the same is adapted to be inserted between the two blocks 9 and 11 with its front 17 located against the plate, its sides 16 lying alongside of the guides 15 and with one end abutting against the lip 13. For the convenient insertion and removal of the containers, the blocks and opposite sides of the plate are recessed at 20 for the fingers of the operator, as is obvious.

The lower block 9 has a central vertical opening 21 therethrough, plate 12 and table 11 having openings vertically alining therewith, and a shaft 22 is mounted vertically therein, the upper end of which comes slightly below the upper face of the plate 12 when the parts are in the position shown in Figs. 1 and 3, whereby there is no interference to the insertion of a container between the blocks. The shaft is mounted in suitable bearings 23 and 23^a connected to suitable supporting beams 24 and 24^a. A pulley 25 is loosely mounted on the shaft 22 and may be continuously driven by a belt 26 from any suitable power source. The lower side of the pulley is shaped to receive a clutch member 27 splined on the shaft and formed with a collar 27^a with which one end of a lever 28 is yoked, the lever being pivotally mounted between its ends on a bracket 28^a carried on the beam 24^a. The other end of lever 28 has pivotal connection with the upper end of a link 29, the lower end of which is pivotally connected to a foot lever 30 between the ends thereof. Lever 30 is pivotally connected at one end to a stationary bracket 31 and is normally elevated by a spring 32 attached at its ends 55 to the lever and the beam 24^a as shown in Fig. 1. It is apparent that clutch member 27 is normally disconnected from the pulley 25 but that the same may be elevated into connection therewith by stepping on the end 60 of the foot lever, whereupon the shaft 22 will be rotated.

The upper end of the shaft 22 has a portion at one side cut away and a pin 33 is set vertically therein a short distance off 65 center of the shaft. When the container

for the belting has been placed between the two blocks 9 and 11, handle 5 is grasped and operated to rotate the eccentric 4, depressing the blocks and thereby carrying the container downwardly a short distance so that 70 the upper end of shaft 22 projects through the opening 18 in the lower side of the container. The hook 34 on the end of a length of belting is inserted into the open end of the container, and said hook is engaged 75 with the pin 33, as the shaft 22 is rotated, the foot lever 30 having been depressed to start the shaft in rotation. This immediately causes the belting 35 to be drawn into the container and wound around the 80 upper end of the shaft 22 into a coil, the entire coil being contained within and covered by the front and back 17 and 19 of the package container as is evident. Sealing strips 36 of paper are then attached at 85 the open ends of the package, the foot lever released, and the eccentric turned to initial position, after which the completed package is removed from the machine and the process repeated for a succeeding package. 90

The above described machine and method of packaging belts is very useful, may be worked with great speed, and by it belts may be coiled and sealed in packages in large quantity at low labor cost. The construction has proved especially useful in practice. It is obvious that variations in constructive detail may be resorted to in the construction of the machine, and the invention is not to be considered as limited 95 strictly thereto but comprises all forms of structure coming within the scope of the claims. 100

I claim:

1. In combination, a support, rods extending upwardly therefrom, upper and lower blocks loosely mounted on the rods, springs between the blocks and between the lower block and the support for normally elevating said blocks, means for manually moving both blocks downwardly, spacing means between the blocks for holding the same a distance apart when both are moved downwardly, a vertical shaft passing upwardly through the lower block and having a vertical pin 110 thereon at its upper end, driving means, and means for connecting the shaft with the driving means at will, substantially as described. 115
2. In combination, a horizontal table, rods extending vertically therefrom, a spring 120 around each rod and resting on the table, a lower block resting on said springs and through which the rods pass, said block having a central vertical opening therethrough, a second spring around each rod resting on 125 the upper side of the lower block, a second upper block bearing on the upper ends of the second springs, a bracket at each end of the blocks, a rod disposed between the upper ends of said brackets, an eccentric on the rod 130

over the upper block, a handle extending from the eccentric, spacer bars disposed between the blocks and attached to one of said blocks, a shaft mounted vertically and extending 5 through the table and into the vertical opening in the lower block, the upper end thereof having one side partly removed and a pin positioned vertically in the recess, and said upper end of the shaft lying slightly below the 10 upper side of the block in the normal position thereof, and means for driving the shaft, substantially as described.

3. A construction containing the elements in combination defined in claim 6, combined 15 with a plate set into the upper side of the lower block and having a central opening therethrough alining with the central opening in the block, said plate at one outer edge having an upturned lip, substantially as and 20 for the purposes described.

4. In a construction of the class described, means for receiving and holding a container having upper and lower sides, and an open end, the lower side having an opening there-

through, a shaft mounted for rotation, means 25 for driving the same, means for moving the container holding means to project the end of the shaft through said opening, and means on the end of the shaft for connecting with a hook on the end of a length of belting, 30 substantially as and for the purposes described.

5. In a construction of the class described, means for receiving and holding a container for belting having one side provided with 35 an opening therethrough, said container having an open end, a shaft mounted for rotation, means for driving the shaft, means for projecting the end of the shaft through said opening in the side of the container, and 40 means on the end of the shaft with which a hook secured at one end of a length of belting may connect to thereby draw the belt- 45 ing into the container and wind the same into a coil around the shaft, substantially as described.

In testimony whereof I affix my signature.

FRANCIS F. RANIVILLE.
